US0D1106107S

(12) **United States Design Patent** (10) **Patent No.:** **US D1,106,107 S**
Xu (45) **Date of Patent:** **** Dec. 16, 2025**

(54) **PERSONAL MEDICAL ALERT BASE STATION**

(71) Applicant: **MICRON ELECTRONICS LLC**,
 Boca Raton, FL (US)

(72) Inventor: **Jun Xu**, Boca Raton, FL (US)

(73) Assignee: **MICRON ELECTRONICS LLC**,
 Boca Raton, FL (US)

(**) Term: **15 Years**

(21) Appl. No.: **29/860,466**

(22) Filed: **Nov. 18, 2022**

Related U.S. Application Data

(63) Continuation-in-part of application No. 29/756,978, filed on Nov. 2, 2020, now Pat. No. Des. 975,045.

(51) **LOC (15) Cl.** **14-03**

(52) **U.S. Cl.** **D14/140; D24/186**

(57) **CLAIM**

The ornamental design for a personal medical alert base station, as shown and described.

DESCRIPTION

FIG. 1 is a top perspective view of a personal medical alert base station showing my new design;

FIG. 2 is a top view thereof;

FIG. 3 is a left view thereof;

FIG. 4 is a right view thereof;

FIG. 5 is a bottom view thereof;

FIG. 6 is a rear view thereof;

FIG. 7 is a front view thereof;

FIG. 8 is a bottom perspective view thereof;

FIG. 9 is another bottom perspective view thereof; and,

FIG. 10 is another bottom perspective view thereof.

1 Claim, 10 Drawing Sheets
